(57) **CLAIM**

The ornamental design for a light fixture, as shown and described.

DESCRIPTION

FIG. 1 is a perspective view of a light fixture in accordance with my design;

FIG. 2 is a sectional view of a light fixture in accordance with my design, taken along the line 2-2 in FIG. 1;

FIG. 3 is a bottom plan view of the light fixture in accordance with my design;

FIG. 4 is a front elevation view of the light fixture in accordance with my design, the opposite view being a mirror image of that shown; and,

FIG. 5 is a side elevation view of the light fixture in accordance with my design, the opposite view being a mirror image of that shown.

The portions of the light fixture shown broken away in FIGS. 1-5 are to depict nonspecific length.

The broken-line disclosure of elements is understood to represent portions of the article in which the design is embodied, but which form no part of the claimed design.

It is certified that error appears in the above-identified patent and that said Letters Patent is hereby corrected as shown below:

On the Cover Page, Item 57 should read:

CLAIM

The ornamental design for a light fixture, as shown and described.

DESCRIPTION

FIG. 1 is a perspective view of a LIGHT FIXTURE in accordance with my design;

FIG. 2 is a top plan view of the LIGHT FIXTURE in accordance with my design;

FIG. 3 is a bottom plan view of the LIGHT FIXTURE in accordance with my design;

FIG. 4 is a front elevation view of the LIGHT FIXTURE in accordance with my design, the opposite view being a mirror image of that shown; and

FIG. 5 is a side elevation view of the LIGHT FIXTURE in accordance with my design, the opposite view being a mirror image of that shown.

The portions of the LIGHT FIXTURE shown broken away in FIGS. 1-5 are to depict nonspecific length.

The broken-line disclosure of elements is understood to represent portions of the article in which the design is embodied, but which form no part of the claimed design.
